UNITED STATES PATENT OFFICE.

LAURA MANGER MYERS, OF CHICAGO, ILLINOIS.

HOLDING-PIN.

1,264,325.

Specification of Letters Patent. Patented Apr. 30, 1918.

Application filed January 5, 1916. Serial No. 70,340.

To all whom it may concern:

Be it known that I, LAURA MANGER MYERS, a citizen of the United States, and resident of Chicago, in the county of Cook and State 5 of Illinois, have invented certain new and useful Improvements in Holding-Pins, of which the following is a specification.

This invention relates more particularly to a pin or device which is especially useful 10 for hemming, Shirring and plaiting; for holding a pattern for cutting; for holding goods for pressing or ironing, and for various other purposes in connection with sewing and the like. Among the objects of this 15 invention are to provide a sewing pin having a plurality of branches which serve to hold the goods straight and evenly; to provide such a pin which may be easily and cheaply made and which will be durable 20 and efficient in use; and to provide such advantages and improvements as will appear from the following description.

In the accompanying drawings illustrating this invention:

25 Figure 1 is a plan view showing two of my improved pins of different sizes inserted in a holder;

Fig. 2 is a view of the blank from which the body portion of the pin is constructed;

30 Fig. 3 is a front view of one of the pins, with a portion broken away to show the construction; and

Fig. 4 is a sectional view taken on the line 4—4 of Fig. 3.

35 As illustrated in these drawings, 5 represents the blank from which the combined body portion or handle of the pin is made, this blank comprising a flat plate of metal such as aluminum, having holes 6 for the 40 sharpened wires 7. There may be any number of these wires used, but in my preferred form three are used. The lower portion 8 of the plate 5 is bent up and flattened against the back of the plate, as shown in Figs. 3 45 and 4, being pressed down over the inner ends of the wires so as to leave projections 9 at the front only of the handle portion. The upper portion 10 is then bent over to form a tubular hand piece 11, which also extends 50 forwardly from the plate, so as to leave the back of the plate entirely flat. The inner edge of the tubular extension is bent in against the upper edge of the portion 8, so as to lock the same securely against the wires. 55 Corks or plugs 12 are inserted in the ends

of the tubular portion 11, so as to make a receptacle for holding pins or needles, or this receptacle may be filled with some perfumed material, in which case the corks 12 may be omitted or may be made of such material as will allow the escape of the odor.

My improved sewing or holding pin may be made in a variety of sizes, two sizes, as indicated at 13 and 14, being shown in Fig. 1, the sharpened wires being inserted in a 65 holder 15, which is made of convenient size for holding the two pins. In this figure the pins are shown about one-third larger than in my preferred form of device. On account of having a plurality of sharpened 70 wires all held in parallel relation, the pin is especially useful for hemming, as it will hold the goods flat and straight instead of permitting them to wrinkle, as is the case when a common single pin is used. In shirring, the pin is useful not only for holding 75 the goods, but also for distributing the shirring rapidly and evenly. It is useful for holding the patterns in cutting, as the pattern will not slip or tear, as with a common pin. It is also useful for holding the 80 plaits for basting; for holding trousers or plaited skirts for pressing; for holding laces or ribbons for ironing; for holding goods for hemstitching or fancy stitching; and in fact 85 is useful in a large variety of instances.

Having thus described my invention, which however I do not wish to limit to the exact construction herein shown and described, except as specified in the following 90 claims, what I claim and desire to secure by Letters Patent is:

1. A holding pin comprising a plate folded upon itself and having holes through the fold and a plurality of sharpened wires 95 clamped between the folded portions of the plate and extending out through said holes.

2. In a device of the character set forth, the combination of a plate having one portion folded back upon itself and having holes 100 through the fold, pins having their inner ends clamped between said folded portions and extending out through said holes, the opposite portion of said plate being bent to form a tubular projection lengthwise of the 105 plate, the inner edge of said portion being pressed against the inner edge of the folded portion to hold said folded portion in position.

LAURA MANGER MYERS.
